CLAIM

The ornamental design for a display screen or portion thereof with a graphical user interface, as shown and described.

DESCRIPTION

FIG. 1 is a front view of a display screen or portion thereof with a graphical user interface showing our new design; and, FIG. 2 is a front view of a second embodiment thereof. The broken line at the periphery of the graphical user interface illustrates the display screen or portion thereof, and the remaining broken lines illustrate portions of the display screen or portion thereof with a graphical user interface. None of the broken lines form part of the claimed design.
